UNITED STATES PATENT OFFICE.

HENRY SHELDON, OF MOORE, MONTANA.

WIRE-BENDING TOOL.

1,031,738.

Specification of Letters Patent.

Patented July 9, 1912.

Application filed August 16, 1911. Serial No. 644,403.

To all whom it may concern:

Be it known that I, HENRY SHELDON, a citizen of the United States, residing at Moore, in the county of Fergus and State 5 of Montana, have invented new and useful Improvements in Wire-Bending Tools, of which the following is a specification.

The invention relates to tools and has for an object to provide pliers for bending wires 10 and the like.

To accomplish the desired result, use is made of relatively pivoted heads provided with teeth and having handles extended therefrom, the said heads each being provided with grooved hemispherical portions 15 and having an aperture formed there-between to slidably receive a headed link, toggle levers being connected to the said link and slidably relatively thereto, the said toggle levers having their outer ends pivotally mounted on the handles so that when a wire is disposed in the grooved portions of the heads and the handles are pressed together the mentioned wire will assume a circular 25 shape, means being provided to adjust the said link relatively to the said heads.

Reference is to be had to the accompanying drawings constituting a part of this specification, in which similar characters of 30 reference denote corresponding parts in all the views, and in which—

Figure 1 is a plan view of my device showing the same in open position, parts being broken away to disclose the underlying 35 structure. Fig. 2 is a similar view showing my device in closed position, parts being broken away to disclose the underlying structure. Fig. 3 is a horizontal sectional view on the line 3—3 in Fig. 2. Fig. 4 is 40 a vertical section on the line 4—4 in Fig. 2. Fig. 5 is a vertical section on the line 5—5 in Fig. 1, looking in the direction of the arrow. Fig. 6 is a plan view of the link member showing the head thereof and the 45 adjusting means thereon.

Referring more particularly to the various views I provide a plurality of jaws 10 relatively mounted to swing on a pin 11 and having handles 12, one of the handles 50 being extended from each of the jaws 10 and integrally formed thereon. One of the handles 12 at the inner end is provided with an integral shoulder 13 and the head of this handle is provided with an integral shoulder 14, the other head being operable 55 between the mentioned shoulders and so

disposed that an aperture 15 will be formed by grooved portions 16 formed on the inner sides of the jaws 10. The outer ends of the jaws 10 terminate in gripping lugs 17 having teeth 18 formed thereon, the said lugs being adapted to engage, thus engaging the teeth on each of the lugs 17 when it is desired to grip a wire or the like; and formed on the jaws 10 adjacent the teeth 18 are 60 65 grooved hemispherical circular portions 19 adapted to substantially form a circle when the gripping lugs engage.

Mounted to slide in the aperture 15 between the jaws 10 and extending up to the 70 grooved portions 19 is a link 20 having a slot 21 through which is extended the pin 11 and the said link is provided with a second slot 22 at one of the ends thereof, the other end of the link 20 terminating in a 75 triangularly shaped head 23. A lug 24 is formed on the upper side of the link 20 and threadedly engaging the said lug is an adjusting screw 25. Pivotedly mounted on the handles 12 are toggle levers 26, one of 80 the levers being connected to each handle and having their other ends pivotally connected and operable in the slot 22 of the link 20.

In the use of my device a rope end is 85 inserted between the jaws 10 and a piece of wire passed over the rope end is also inserted between the jaws 10, the jaws being in open position. Now by pressing the handles 12 together, the jaws 10 will coact so 90 that the piece of wire will be bent around the rope end and assume a circular shape owing to the hemispherical grooves 19 in the jaws 10, and when the handles are pressed together, as mentioned, the toggles 95 will force the link forwardly so that the head 23 will engage the wire. By exerting a strong pressure on the handles when they are pressed together the wire will be securely bent around the rope end and rigidly positioned thereon to prevent the strands of the 100 rope from unraveling at the ends. When the tool is in closed position the toggle levers operating in the slot 22 at their point of connection will engage an end of the screw 105 25 and by adjusting the screw 25 the movement of the link 20 relatively to the jaws 10 can be adjusted so that the extension of the link between the jaws 10 can be increased or decreased according to the size of rope 110 end that is inserted between the jaws and to which it is desired to secure a piece of

wire. By providing the teeth 18 on the lugs 17 my device can also be used as tweezers or pliers to disengage a wire secured to a rope end.

5 Although I have shown and described my tool as applied to secure wires to rope ends, it will be understood that I do not limit myself to this construction and description and that the scope and construction of the invention is defined in the appended claims.

Having thus fully described the invention, what I claim as new, is:—

15 1. A tool comprising a plurality of relatively pivoted jaws, handles extended outwardly from the said jaws, the said jaws being provided with hemispherical grooved portions and having a longitudinally extending aperture formed therebetween, a 20 link slidably mounted in the said aperture, a head formed on the said link and normally positioned adjacent the said grooved portions, the said link being provided with a slot at the outer end thereof, toggle levers 25 pivotally connected to the said handles and slidable in the slot of the said link, and an adjusting screw mounted on the said link and adapted to engage the inner ends of the 30 said toggle levers to adjust the same relatively to the said links.

2. A tool comprising a pair of relatively pivoted jaws, teeth formed on the outer ends of the said jaws, handles extended from the other ends of the said jaws, a link slidably mounted between the said jaws and provided with a slot at one end thereof, toggle levers pivotally connected to the said handle and slidable in the slot of the said link, and

means mounted on the said link and adapted to engage the said toggle levers to adjust the same relatively to the said link.

3. A tool comprising a plurality of jaws, a pin pivotally connecting the said jaws, handles extended from the said jaws, a link slidably mounted between the said jaws, the 45 said link being adapted to slide relatively to the said jaws when the said handles are operated, and means mounted on the said link for adjusting the same relatively to the said jaws.

4. In a tool, the combination of a plurality of relatively pivoted jaws having hemispherical grooves therein, integral gripping lugs formed on the outer ends of the said jaws, teeth formed on the said lugs, handles integrally formed on the said jaws and extended therefrom, a slotted link mounted to slide relatively to the said jaws, toggle levers pivotally mounted on the said handles and slidable in the slot of the said link, a 60 head integrally formed on the outer end of the said link and normally disposed adjacent the said hemispherical grooves, an apertured bearing mounted in the said link, and an adjusting screw extended through 65 the aperture in the said bearing and engaging the said toggle levers to adjust the same relatively to the said link and limit the movement of the said link relatively to the said jaws.

In testimony whereof I affix my signature in presence of two witnesses.

HENRY SHELDON.
